CLAIM

We claim the ornamental design for a automatic rifle safety plug indicator, as shown and described.

DESCRIPTION

FIG. 1 is a perspective view of the automatic rifle safety plug indicator, showing our new design;
FIG. 2 is another perspective view thereof;
FIG. 3 is a rear plan view thereof;
FIG. 4 is a front plan view thereof;
FIG. 5 is a top plan view thereof;
FIG. 6 is the bottom plan view thereof;
FIG. 7 is a left side plan view thereof; and,
FIG. 8 is a right side plan view thereof.
